PIVOTED LUG CONVEYER

Farwell G. Bemis, Brookline, Mass., and Robert E. Pierce, Seattle, Wash., assignors to Bemis Bro. Bag Company, St. Louis, Mo., a corporation of Missouri

Application June 8, 1946, Serial No. 675,460

12 Claims. (Cl. 198—170)

1

This invention relates to conveyors, and with regard to certain more specific features, to a lug type of conveyor.

Among the several objects of the invention may be noted the provision of a constant-speed, lug type of conveyor in which the feeding lugs may readily be selectively spaced for accommodating between them articles of various dimensions; the provision of a conveyor of the class described in which lug spacing operations are easily carried out; the provision of apparatus of the class described in which adjustments are easily made at one point on the machine and wherein required compensations elsewhere are automatically introduced; and the provision of apparatus of this class which is reliable and economical to construct. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which one of various possible embodiments of the invention is illustrated,

Fig. 1 is a top plan view of essential parts of the invention, parts being broken away;

Fig. 2 is a front elevation of Fig. 1;

Fig. 3 is a right-end view of Figs. 1 and 2;

Fig. 4 is a horizontal section taken on line 4—4 of Fig. 2, showing certain adjusted positions of parts;

Figs. 5 and 6 are views similar to Fig. 4 but showing other adjustments;

Fig. 7 is an enlarged detail section viewed from line 7—7 of Fig. 2, parts being broken away; and,

Fig. 8 is a front elevation of Fig. 7 and a vertical section taken on line 8—8 of Fig. 1 but omitting a lug support.

Similar reference characters indicate corresponding parts throughout the several views of the drawings.

Referring now more particularly to Figs. 1—3, numeral 1 indicates a frame, at one end of which are oppositely disposed bearings 3 and 5, supporting a drive shaft 7. The drive shaft is turned by chain drive 9 extending from a suitable power source (not shown). The power source may be a motor and speed reduction unit.

Attached to the shaft 7 is a pair of equal-sized sprockets 11 and 13 for driving endless and parallel conveyor chains 15 and 17, respectively. The chains 15 and 17 at their other ends pass

2

over larger equal-sized sprockets 19 and 21, respectively. The sprockets 19 and 21 are attached to a shaft 23 which is rotary in bearings 25 and 27, the latter being carried on suitable supports 29 and 31 attached to the frame 1.

The chains 15 and 17 are similar in form, details being shown in Figs. 7 and 8. Certain side plates 37 are of special form, having laterally extending tongues 39. Riveted to the tongues 39 and extending upward are dogs 41. Carried on the dogs 41 are horizontal pins 43, located parallel to the respective chain. Pivoted on the dogs 41 are laterally extending lugs 45. The lugs 45 may be positioned laterally, as shown by three lugs in Figs. 7 and 8, or vertically, as shown by one lug in said figures.

Beneath each reach of each chain 15 and 17 is a fixed chain support 53, as shown for example in Figs. 7 and 8.

Along the upper reach of each chain is located a pair of guides 47 and 49. These guides are spaced apart, as indicated at 51, thus providing a slot through which any upright lug 45 may move, if properly positioned for the purpose. Beneath the guide 49 is an upper lug support 55. This lug support 55 supports any laterally extending lug which is not turned up into position in the space 51.

Near each small sprocket 11 and 13 is located 30 the turned-up end of a lower lug support 57. Each turned-up end forms a cam 59. The face of each cam 59 extends crosswise with respect to the end of the respective groove 51. Thus each cam 59 will angle out of the plane of its chain 35 any upright lug departing from slot 51. This occurs as the adjacent part of the chain passes over the respective sprocket. As all lugs 45 return along the bottom reach of the chain, they are supported by the lower lug support 57. The rear 40 end of each lower lug support 57 partially follows the periphery of the respective large sprocket 19 or 21, as indicated at 61, and ends just short of the entry to the slot 51. A clear space 63 is thus left for travel of the lugs 45 as they leave the lower lug support 57 and as they arrive at the upper guides 47 and 49 (Fig. 2).

If any laterally extending lug 45, when it reaches the space 63, is not mechanically pushed into a radial position, it will not enter the slot 51. The centrifugal force is not enough to accomplish this at useful operating speeds. If a lug is mechanically pushed, it will enter said space 51. To provide for mechanically pushing select lugs 45 into position in the slot 51 to obtain predetermined 50 lug spacing, the following mechanism is used:

Near each space 63 is an angled bearing 65. These bearings support trip mechanisms 67 and 69, associated with the chains 15 and 17, respectively. Each trip mechanism consists in a rotary head 71 carried on a shaft 73 which is rotary in the bearing 65. The lower ends of the shafts 73 carry bevel gears 75 meshed with bevel gears 77 carried on a shaft 79. The latter has a rotary support in bearings 81 on the frame 1. Shaft 79 also carries a bevel gear 83 which meshes with a bevel gear 85 on a lay shaft 87. A yoke 89 properly relates the gears 83, 85 and shafts 89 and 87.

At its other end, the lay shaft 87 has a gear connection with a cross shaft 91 through bevel gears 93 and 95, an alignment yoke 97 being employed. The shaft 91 is supported in bearings 99 and 101. It passes through the bearing 101, where it is provided with a crank arm 103 in which is a slot 105. A roller 107 is operative in the slot 105, being carried on a pin 109 in the end of a second crank arm 111. This crank arm is carried upon a shaft 113 carried in a movable bearing 115. The opposite end of shaft 113 carries a change gear at 117, which gear meshes with an idler gear 116. Gear 116 meshes with gear 119 on shaft 7 above described. Gear 116 is mounted on a stub shaft 118 located in the support for bearing 5 (Figs. 2 and 4-6).

The bearing 115 is adjustable, being carried upon a slide 121 which is supported on a guide 123. Rotary in a bearing 125 which is connected to the guide 123 is a threaded shaft 127. This shaft is threaded into a nut portion 131, associated with the bearing 115 and is under control of an attached handwheel 129. By turning the handwheel 129, the position of the slide 121 may be adjusted on the guide 123, thus making it possible to change the relative positions of the center lines of the shafts 113 and 91. Thus said center lines may be related, as shown in Fig. 4, wherein a small gear at 117 is used; or, as shown in Fig. 5, wherein a larger gear is used at 117; or as shown in Fig. 6, wherein a still larger gear is used at 117. It will be understood that the gears to be located at 117 are all removably keyed to the end of the shaft 113.

The parts 113, 111, 107, 105, 103 and 91 constitute an adjustable variable-drive mechanism, a similar one being shown for different purposes in United States Patent 2,119,024. The new co-ordination and purpose herein of this variable-drive mechanism will appear. In some of the claims hereinafter the term "swinging block linkage" is used to designate this mechanism consisting of the relatively adjustable cranks 111 and 103 on their shafts 113 and 91, respectively, together with the guide means 105 in the crank 103 with the member 107 movable in the groove 105. Equivalents of member 107 are a block slider, or a plain round gudgeon, instead of the roller shown.

Operation is as follows:

The shaft 7 is driven at a suitable speed from the chain drive 9, the motion being as shown by the arrows in Figs. 1 and 2. This causes the upper reaches of the chains 11 and 13 to move to the right. Shaft 7 rotates the drive shaft 113 of the quick-return mechanism. This is brought about by the gears 119, 116 and the selected gear at 117. Shaft 91 drives shaft 79 through gears 95, 93, shaft 87 and gears 85 and 83. The trip mechanisms 67 and 69 are thus oppositely rotated through action of the bevel gear sets 77 and 75. Each head 71 carries a finger 133, which as the head rotates is adapted to approach and pass

through the space 63 on a bias and in a direction radially to move whatever lug 45 happens to be traveling in the space 63. This action is illustrated in Fig. 1. The respective lug 45 is thrown into the position to enter the slot 51, wherein it advances forward as also illustrated in Figs. 1, 2 and 3.

When the shafts 113 and 91 are coaxial, or nearly so, as shown in Fig. 5, the velocities of the fingers 133 are such as to effect a proper striking action between the fingers 133 and the engaged lugs 45. Thus the lugs are moved quickly enough to enter slot 51, but they do not improperly spring back when engaging the stop formed by the end of the guide 49.

Successive rotations of the trip mechanisms 67 and 69 cause spaced lugs 45 to enter the slot 51, after which they advance forward. The design is arranged so that the spacing between the successive lugs in a slot 51, measured in inches, is equal to the number of teeth chosen for the respective interchangeable gear at 117. For instance, this gear at 117 in Fig. 2 has fourteen teeth and the spacing between successive dogs is therefore 14 inches.

As the successive raised lugs leave the opposite ends of the slots 51, they strike the cam fingers 59 and are rotated into lateral positions for support upon the dog support 57 for return along the lower reach of the chain to the space 63.

As indicated by dot-dash lines in Fig. 3, a suitable table 135 is arranged flush with the grooves 51 so that any article may be pushed by the upwardly extending spaced lugs 45.

If it is desired to change the spacing between successive lugs 45 in each groove 51, this is accomplished by changing the respective gear at 117. Each slide 121 may be backed off by operating the respective hand wheel 129, and (for example) gears of eleven teeth inserted at 117. The slide 121 is then returned to mesh the gears at 117 with the gears at 116. This will result in a faster periodic timing of the shaft 113 and consequently also of the shaft 91 and its drive to the trip mechanisms 67 and 69. Hence more lugs 45 will be moved into positions in the slots 51, thus decreasing their spacings. In this case the spacing between successive lugs 45 would be 11 inches, assuming an 11-tooth gear at 117.

However, this ordinarily would involve a higher linear speed of each finger 133, with the possibility of too high a velocity in connection with the tripped lugs 45. In other words, these lugs might bounce back from the stop end of guide 49 and miss the slot 51. It is to avoid such action that the mechanism shown in Figs. 4-6 is used. In the adjustment under discussion (shown in Fig. 4) the speeds of shaft 113 and 91 have been increased but the cyclic timing between them is still 1:1. But during a cycle the shaft 91 accelerates and decelerates throughout a revolution, producing maximum and minimum velocities. These velocities are transmitted to the trip mechanisms 67 and 69 and their fingers 133. Thus when the center line of the shaft 113 is to the left of the center line of shaft 91, the fingers 133 reach a minimum velocity as they approach engagement with the lugs 45. Then throughout the remaining portion of a cycle, the fingers 133 accelerate and make a quick return and then are decelerated for their next low-velocity contacts with the lugs 45.

This minimum velocity is closer to the mean velocity under the Fig. 5 conditions than would be the case without a variable-speed apparatus for the purpose.

If it is desired to increase the distance between successive dogs 45, this is accomplished by adjusting the slide 123, as shown in Fig. 6, wherein the center line of shaft 113 is placed to the right of the center line of shaft 91. This requires a larger gear at 117, for example, a 28-tooth gear which produces a 28-inch distance between successive lugs 45 which are tripped out by the respective fingers 133. The resulting slower velocity of the trip mechanisms 67 and 69, which would be brought about by insertion of the larger gear 117 and without the variable-speed mechanism, would cause a linear velocity of the fingers 133 which would be too low properly to actuate the lugs 45 without interference from succeeding dogs. In other words, under these conditions the fingers 133 would pass too slowly through the space at 63. The variable-speed mechanism, in the Fig. 6 adjusted position, avoids this trouble, because in this adjustment fingers 133 accelerate as they approach respective openings 63. They then pass through the openings at maximum speeds and throughout the remaining parts of their cycles return at lower speeds.

It will be understood that, whether the mechanism is adjusted as in Fig. 4 for a quick return, or as in Fig. 6 for a slow return, the instantaneous velocities of the fingers 133 through the respective openings 63 are closer to the average velocities under the adjustment than would be the case without the variable-speed mechanism.

It should be understood that the adjustments shown in Figs. 2, 4, 5 and 6 are not the only ones, and that other gears may be placed at 117, having other numbers of teeth which correspond to the desired spacing in inches between the lugs 45 which are in the slots 51. It will be seen, however, that for each gear which is used, at 117 and properly meshed with the gear 116, an adjustment of the shaft 113 is automatically obtained which sets the variable-speed mechanism so that the fingers 133 pass through the space 63 at the proper speed for correctly operating the lugs 45 to be turned into the slots 51.

From Fig. 1, it will be noted that on each shaft 73 is a fixed shoulder 2 upon which rests the respective head 71, a central opening in each head centering it around shaft 73. Each head 71 carries an arcuate slot 4 accommodating a lock bolt 6 threaded into the respective shoulder 2 so that the phase angles of the fingers 133 may be adjusted and locked in adjusted positions. Another important feature of the travel of each finger 133 is its angularity with respect to the direction of motion of the adjacently moving lugs 45. This angularity for a short distance at the openings 63 produces substantially equal tangential components of travel of the fingers 133 and lugs 45. Thus there is ample contact time between the fingers 133 and the lugs 45 for proper actuation, and to keep a moving finger 133 out of the way of a succeeding lug 45.

It will be understood that the use of chains to support the adjustable dogs is preferable, but that other flexible connectors may be used for this purpose, such as belts or the like. They all serve to concatenate the dogs.

In view of the above, it will be seen that the several objects of the invention are achieved and other advantageous results attained.

As many changes could be made in the above constructions without departing from the scope of the invention, it is intended that all matter contained in the above description or shown in

the accompanying drawings shall be interpreted as illustrative and not in a limiting sense.

We claim:

1. A conveyor comprising an endless flexible connector mounted for movement along opposite reaches, initially positioned swingable lugs mounted in succession on said flexible connector, means providing a slot along one reach of the connector into the inlet of which some of said lugs may be turned, cyclic trip means at the slot inlet adapted to turn lugs therein, means at the outlet end of the slot for returning said lugs to their initial positions relative to the flexible connector, means for varying the timing of the cycles of said trip means relatively to lug movement, and a cyclic variable-speed drive for the trip means for maintaining a substantially predetermined velocity of the trip means during tripping movements only, irrespective of the timing of the cycle thereof.
2. A conveyor comprising an endless chain, means for driving the chain with substantially constant speed along upper and lower reaches, laterally swingable lugs mounted in succession on said chain, means providing a slot along the upper reach of the chain into which any of said lugs may be turned, cyclic trip means at the inlet end of said slot adapted to turn lugs therein, means in the outlet end of the slot for returning said lugs to their initial positions relative to the chain, means including a change-gear for varying the period of the cyclic action of said trip means, an adjustable variable-speed drive for the trip means, means whereby adjustments of said variable-speed drive effect accommodation of various change gears, whereby a substantially constant tripping action of the trip means is maintained irrespective of the timing of the cycle thereof.
3. A conveyor comprising an endless chain, means for driving the chain with substantially constant speed along upper and lower reaches, laterally swingable lugs mounted in succession on said chain, means providing a slot along the upper reach of the chain into which any of said lugs may be turned, cyclic trip means at the inlet end of said slot adapted to turn lugs therein, means in the outlet end of the slot for returning said lugs to their initial positions relative to the chain, means including a change gear for varying the period of the cyclic action of said trip means, an adjustable variable-speed drive for the trip means, means whereby adjustments of said variable-speed drive effect accommodation of various change gears, whereby a substantially constant tripping action of the trip means is maintained irrespective of the timing of the cycle thereof, said trip means being arranged so as to have a component of motion along the direction of lug motions where they enter the slot, said component of motions and said lug motions being substantially equal under all adjustments.
4. A conveyor comprising an endless flexible connector mounted for movement along upper and lower reaches in a substantially vertical plane, laterally swingable lugs mounted in succession on said flexible connectors, means providing a slot along the upper reach of the connector into which any of said lugs may be tripped, cyclic trip means at the inlet end of said slot for tripping lugs therein, means at the outlet end of the slot for returning said lugs to their initial positions relative to the flexible connector, change-speed means for changing the cyclic timing of said trip means relative to connector move-

ment, a variable-speed drive for the trip means for maintaining a substantially constant tripping action irrespective of the timing of the cyclic timing thereof, and means for coordinating the change-speed means and said variable-speed means whereby any selection of a given cyclic period will result automatically in proper adjustment of said variable-speed means to effect said constant tripping action.

5. A conveyor comprising a moving endless chain, a guide associated with one reach of said chain, a succession of laterally movable lugs on said chain which are moved by said chain, cyclic trip means for moving successive lugs toward the guide, a connection between the chain and the trip means for cycling the trip means in unison with the motion of the chain, and a variable-speed mechanism in said connection whereby the speed of the trip means is varied throughout a cycle thereof in such a manner that engagement between the trip means and the lugs is substantially at a predetermined velocity.

6. A conveyor comprising a moving endless chain, a guide associated with one reach of said chain, a succession of laterally movable lugs on said chain which are translated by said chain, cyclic trip means, an adjustable-speed driving connection between the chain and the trip means for cycling the trip means in unison with the motion of the chain but according to different and adjustable periods, and a variable-speed mechanism in said connection whereby the speed of the trip means is varied throughout a cycle thereof in such a manner that engagement between the trip means and the lugs is always substantially at a given velocity, irrespective of the adjustment of said adjustable-speed connection.

7. A conveyor comprising an endless chain, a guide associated with one reach of said chain, a succession of laterally movable lugs on said chain normally movable by said chain, cyclic trip means for moving successive lugs toward the guide, power means for driving the chain, a driving connection between the chain and the trip means for cycling the trip means in unison with the motion of the chain, a change-gear mechanism in said connection for changing the cycling period of said trip means, a variable-speed mechanism in said connection whereby the speed of the trip means is varied throughout a cycle thereof in such a manner that engagement between the trip means and the lug is always substantially at a given velocity.

8. In apparatus of the class described, a movable member, shiftable lugs on said member, means for driving said member at a given speed, trip means for moving said lugs with respect to the member, change-speed apparatus connected between said member and said trip means whereby the two may be driven according to variously timed cyclic relationships, and a variable-speed connection in series with said change-speed apparatus adapted to accelerate and decelerate said trip means throughout each cycle of its action.

9. In apparatus of the class described, a flexible connector, shiftable lugs on said connector, means for driving said connector at a substantially constant speed, trip means for moving said lugs with respect to the connector, a change-speed drive connected between said flexible connector

5 and said trip means whereby the two may be driven according to variously timed cyclic relationships, and a variable-speed connection associated with said change-speed connection adapted to accelerate and decelerate said trip means throughout each cycle of its action.

10. In apparatus of the class described, a chain, lugs movable on said chain, means for driving the chain at a substantially constant speed, rotary trip means for moving successive lugs with respect to the chain, a drive connection between said chain and said rotary trip means, a change-gear connection in said drive for varying the periodicity of the rotary trip means with respect to motion of the chain, and an adjustable swinging block linkage in said connection for accelerating and decelerating the trip means throughout one cycle of its action.

11. In apparatus of the class described, a chain, lugs movable on said chain, means for driving the chain with the lugs at a substantially constant speed, a rotary trip finger having a biased movement relative to the chain during part of the finger rotation for optimum movement of successive lugs with respect to the chain, a drive connection between said chain and said rotary trip finger, a change-gear connection in said drive for varying the periodicity of the trip finger rotation with respect to motion of the connector, and a swinging block linkage in said connection for accelerating and decelerating the trip finger throughout one cycle of rotation.

12. In apparatus of the class described, a flexible connector, lugs movable on said connector, means for driving the connector with the lugs at a substantially constant speed, rotary trip means for moving successive lugs with respect to the connector, a drive connection between said connector and said rotary trip means, a change-gear connection in said drive for varying the periodicity of the rotary trip means with respect to motion of the connector, a swinging block linkage in said connection for accelerating and decelerating the trip means throughout one cycle of its action, and means for adjusting said sliding block linkage and at the same time re-orienting the change-speed gear to accept a different gear, whereby regardless of the period of the cyclic action between the trip mechanism and the flexible connector a proper tripping action on the lugs may be obtained from said trip means.
